CONVERSION OF HYDROCARBONS

Jacque C. Morrell and Aristid V. Grosse, Chicago,
Ill., assignors to Universal Oil Products Com-
pany, Chicago, Ill., a corporation of Delaware

No Drawing. Original No. 2,124,584, dated July
26, 1938, Serial No. 103,394, September 30, 1936.
Application for reissue September 15, 1939,
Serial No. 295,198

8 Claims. (Cl. 260—668)

This invention relates particularly to the conversion of straight chain hydrocarbons into closed chain or cyclic hydrocarbons.

More specifically it is concerned with a process involving the use of special catalysts and specific conditions of operation in regard to temperature, pressure and time of reaction whereby aliphatic hydrocarbons can be efficiently converted into aromatic hydrocarbons.

10 In the straight pyrolysis of pure hydrocarbons or hydrocarbon mixtures such as those encountered in fractions from petroleum or other naturally occurring or synthetically produced hydrocarbon mixtures the reactions involved 15 which produce aromatics from paraffins and olefins are of an exceedingly complicated character and cannot be very readily controlled.

It is generally recognized that, in the thermal decomposition of hydrocarbon compounds or hydrocarbon mixtures of relatively narrow range that whatever intermediate reactions are involved, there is an overall loss of hydrogen, a tendency to carbon separation and a generally wider boiling range in the total liquid products as compared with the original charge. Under mild cracking conditions involving relatively low temperatures and pressures and short times of exposure to cracking conditions it is possible to some extent to control cracking reactions so that 20 they are limited to primary decompositions and there is a minimum loss of hydrogen and a maximum production of low boiling fractions consisting of compounds representing the fragments of the original high molecular weight compounds.

25 As the conditions of pyrolysis are increased in severity using higher temperatures and higher times of exposure to pyrolytic conditions, there is a progressive increase in loss of hydrogen and a large amount of secondary reactions involving 30 recombination of primary radicals to form polymers and some cyclization to form naphthenes and aromatics, but the mechanisms involved in these cases are of so complicated a nature that very little positive information has been evolved in spite of the large amount of experimentation which has been done and the large number of theories proposed. In general, however, it may be said that starting with paraffin 35 hydrocarbons representing the highest degree of saturation that these compounds are changed progressively into olefins, naphthenes, aromatics, and finally into carbon and hydrogen and other light fixed gases. It is not intended to infer from this statement that any particular success has

attended the conversion of any given paraffin or other aliphatic hydrocarbon into an aromatic hydrocarbon of the same number of carbon atoms by way of the progressive steps shown. If this is done it is usually with very low yields which are 5 of very little practical significance.

The search for catalysts to specifically control and accelerate desired conversion reactions among hydrocarbons has been attended with the usual difficulties encountered in finding catalysts 10 for other types of reactions since there are no basic laws or rules for predicting the effectiveness of catalytic materials and the art as a whole is in a more or less empirical state. In using catalysts even in connection with conversion reactions among pure hydrocarbons and particularly in connection with the conversion of the relatively heavy distillates and residua which are available for cracking, there is a general tendency for the decomposition reactions to proceed at 20 a very rapid rate, necessitating the use of extremely short time factors and very accurate control of temperature and pressure to avoid too extensive decomposition. There are further difficulties encountered in maintaining the efficiency of catalysts employed in pyrolysis since there is usually a rapid deposition of carbonaceous materials on their surfaces and in their pores. 25

The foregoing brief review of the art of hydrocarbon pyrolysis is given to furnish a general 30 background for indicating the improvement in such processes which is embodied in the present invention, which may be applied to the treatment of pure paraffin or olefin hydrocarbons, hydrocarbon mixtures containing substantial percentages of paraffin hydrocarbons such as relatively close cut fractions producible by distilling petroleum, and analogous fractions which contain unsaturated as well as saturated straight chain hydrocarbons, such fractions resulting 35 from cracking operations upon the heavier fractions of petroleum.

In one specific embodiment the present invention comprises the conversion of aliphatic hydrocarbons including paraffin and olefin hydrocarbons into aromatic hydrocarbons by subjecting them at elevated temperatures of the order of 400-700° C., to contact for definite times of the order of 6-50 seconds with catalytic materials comprising major proportions of refractory carriers of relatively low catalytic activity supporting minor proportions of compounds of elements selected from those occurring in the lefthand column of Group V of the periodic table, these compounds having relatively high catalytic activity. 40 45 50 55

According to the present invention aliphatic or straight chain hydrocarbons having 6 or more carbon atoms in chain arrangement in their structure are specifically dehydrogenated in such a way that the chain of carbon atoms undergoes ring closure with the production in the simplest case of benzene from n-hexane or n-hexene and in the case of higher molecular weight paraffins of various alkyl derivatives of benzene. Under properly controlled conditions of times of contact, temperature and pressure very high yields of the order of 75 to 90% of the benzene or aromatic compounds are obtainable which are far in excess of any previously obtained in the art either with or without catalysts. For the sake of illustrating and exemplifying the types of hydrocarbon conversion reactions which are specifically accelerated under the preferred conditions by the present types of catalysts, the following structural equations are introduced:

In the foregoing table the structural formulas of the primary paraffin hydrocarbons have been represented as a nearly closed ring instead of by the usual linear arrangement for the sake of indicating the possible mechanisms involved. No attempt has been made to indicate the possible intermediate existence of mono-olefins, diolefins, hexamethylenes or alkylated hexamethylenes which might result from the loss of various amounts of hydrogen. It is not known at the present time whether ring closure occurs at the loss of one hydrogen molecule or whether dehydrogenation of the chain carbons occurs so that the first ring compound formed is an aromatic such as benzene or one of its derivatives. The above three equations are of a relatively simple character indicating generally the type of reactions involved but in the case of n-paraffins or mono-olefins of higher molecular weight than the octane shown and in the case of branch chain compounds which contain various alkyl substituent groups in different positions along the six-carbon atom chain, more complicated reactions will be involved. For example, in the case of such a primary compound as 2,3-dimethyl hexane the principal resultant product is apparently o-xylene although there are concurrently produced definite yields of such compounds as ethyl benzene indicating an isomerization of two substituent methyl groups. In the case of nonanes which are represented by the compound 2,3,4-trimethyl hexane, there is formation not only of mesitylene but also of such compounds as methyl ethyl benzol and various propyl benzols.

75 It will be seen from the foregoing that the

scope of the present invention is preferably limited to the treatment of aliphatic hydrocarbons which contain at least 6 carbon atoms in straight chain arrangement. In the case of paraffin hydrocarbons containing less than 6 carbon atoms in linear arrangement, some formation of aromatics may take place due to primary isomerization reactions although obviously the extent of these will vary considerably with the type of compound and the conditions of operation. The process is readily applicable to paraffins from hexane up to dodecane and their corresponding olefins. With increase in molecular weight beyond this point the percentage of undesirable side reactions tends to increase and yields of the desired alkylated aromatics decrease in proportion.

The present invention is characterized by the use of a particular group of composite catalytic materials which employ as their base catalysts certain refractory oxides and silicates which in themselves may have some slight specific catalytic ability in the dehydrogenation and cyclization reactions but which are improved greatly in this respect by the addition of certain promoters or secondary catalysts in minor proportions. These base supporting materials are preferably of a rugged and refractory character capable of withstanding the severe use to which the catalysts are put in regard to temperature during service and in regeneration by means of air or other oxidizing gas mixtures after they have become fouled with carbonaceous deposits after a period of service. As examples of materials which may be employed in granular form as supports for the preferred catalytic substances may be mentioned the following:

Magnesium oxide	Montmorillonite clays
Aluminum oxide	Kieselguhr
Bauxite	Crushed firebrick
Bentonite clays	Crushed silica

Glauconite (greensand)

It should be emphasized that in the field of catalysis there have been very few rules evolved which will enable the prediction of what materials will catalyze a given reaction. Most of the catalytic work has been done on a purely empirical basis, even though at times certain groups of elements or compounds have been found to be more or less equivalent in accelerating certain types of reaction.

In regard to the base catalytic materials which are preferably employed according to the present invention, some precautions are necessary to insure that they possess proper physical and chemical characteristics before they are impregnated with the promoters to render them more efficient. In regard to magnesium oxide, which may be alternatively employed, this is most conveniently prepared by the calcination of the mineral magnesite which is most commonly encountered in a massive or earthy variety and rarely in crystal form, the crystals being usually rhombohedral. In many natural magnesites the magnesium oxide may be replaced to the extent of several percent by ferrous oxide. The mineral is of quite common occurrence and readily obtainable in quantity at a reasonable figure. The pure compound begins to decompose to form the oxide at a temperature of 350° C., though the rate of decomposition only reaches a practical value at considerably higher temperatures, usually of the order of 800° C., to 900° C. Magnesite is related to dolomite, the mixed carbonate of calcium and magnesium,

which latter mineral, however, is not of as good service as the relatively pure magnesite in the present instance. Magnesium carbonate prepared by precipitation or other chemical methods may 5 be used alternatively in place of the natural mineral, as a more reactive constituent of carriers consisting of spacing materials of relatively inert character and in some cases allowing the production of catalysts of higher efficiency and 10 longer life. It is not necessary that the magnesite be completely converted to oxide but as a rule it is preferable that the conversion be at least over 90%, that is, so that there is less than 10% of the carbonate remaining in the ignited material. 15 Aluminum oxide which is generally preferable as a base material for the manufacture of catalysts for the process may be obtained from natural aluminum oxide minerals or ores such as bauxite or carbonates such as dawsonite by proper 20 calcination, or it may be prepared by precipitation of aluminum hydrate from solutions of aluminum sulfate or different alums, and dehydration of the precipitate of aluminum hydroxide by heat, and usually it is desirable and advantageous 25 to further treat it with air or other gases, or by other means to activate it prior to use.

Two hydrated oxides of aluminum occur in nature, to-wit, bauxite having the formula $Al_2O_3 \cdot 2H_2O$ and diasporite $Al_2O_3 \cdot H_2O$. In both of 30 these oxides iron sesqui-oxide may partially replace the alumina. These two minerals or corresponding oxides produced from precipitated aluminum hydroxide are particularly suitable for the manufacture of the present type of catalysts 35 and in some instances have given the best results of any of the base compounds whose use is at present contemplated. The mineral dawsonite having the formula $Na_3Al(CO_3)_3 \cdot 2Al(OH)_3$ is another mineral which may be used as a source of 40 aluminum oxide.

It is best practice in the final steps of preparing aluminum oxide as a base catalyst to ignite for some time at temperatures within the same approximate range as those employed in the ignition of magnesite, to-wit, from 800-900° C. This probably does not correspond to complete dehydration of hydroxides but apparently gives a catalytic material of good strength and porosity so that it is able to resist for a long period of 45 time the deteriorating effects of the service and regeneration periods to which it is subjected. In the case of the clays which may serve as base catalytic materials for supporting promoters, the better materials are those which have been acid-treated to render them more siliceous. These 50 may be pelleted or formed in any manner before or after the addition of the promoter catalyst since ordinarily they have a high percentage of fines. The addition of certain of the promoters, 55 however, exerts a binding influence so that the formed materials may be employed without fear of structural deterioration in service.

Our investigations have also definitely demonstrated that the catalytic efficiency of such substances as alumina, magnesium oxide, and clays which may have some catalytic potency in themselves is greatly improved by the presence of compounds of the preferred elements in relatively minor amounts, usually of the order of less 60 than 10% by weight of the carrier. It is most common practice to utilize catalysts comprising 65 2 to 5% by weight of these compounds, particularly their lower oxides.

The promoters which are used in accordance 70 with the present invention to produce active cat-

alysts from the base materials include generally compounds and more particularly oxides of the elements in the lefthand column of Group V of the periodic table including vanadium, columbium and tantalum. In general practically all 5 of the compounds of the preferred elements will have some catalytic activity though as a rule the oxides and particularly the lower oxides are the best catalysts. Catalyst composites may be prepared by utilizing the soluble compounds of the 10 elements in aqueous solutions from which they are absorbed by prepared granular carriers or from which they are deposited upon the carriers by evaporation of the solvent. The invention further comprises the use of catalyst composites 15 made by mixing relatively insoluble compounds with carriers either in the wet or the dry condition. In the following paragraphs some of the compounds of the elements listed above are given 20 which are soluble in water and which may be used to add catalytic material to carriers. The known oxides of these elements are also listed.

VANADIUM

Catalysts comprising 2 to 5 percent by weight 25 of the lower oxides of vanadium such as the sesquioxide V_2O_3 and the tetroxide V_2O_4 may be used. Some of the monoxide VO may be present 30 in some instances. The oxides mentioned are particularly efficient as catalysts for the present types of reactions but the invention is not limited to their use but may employ other compounds of vanadium. Thus solutions of the ammonium and the alkali metal vanadates may be employed to 35 add vanadium compounds to the carriers and also the soluble vanadyl sulfates and the vanadium nitrate and carbonate. The alkaline earth vanadates may be mixed mechanically and also the halides of vanadium. The oxides per se or those 40 produced by reduction or decomposition of other vanadium compounds are preferred.

COLUMBIUM

A properly prepared carrier may be ground and 45 sized to produce granules of relatively small mesh of the approximate order of from 4 to 20 and these caused to absorb compounds which will ultimately yield compounds of columbium on heating to a proper temperature by stirring them with warm aqueous solutions of soluble columbium compounds, such as for example the mixed fluoride of columbium and potassium already mentioned having the formula $CbOF_2 \cdot 2KF \cdot H_2O$, which is sufficiently soluble in water to render 50 it utilizable as a source of columbium catalyst. Other soluble compounds which may be used to form soluble compounds which may be used to 55 form catalytic deposits containing columbium are the various alkali metal columbates. Still other compounds of columbic acids, including salts of the alkaline earth and heavy metals, may be distributed upon the carriers by mechanical mixing either in the wet or the dry condition. As a 60 rule the lower oxides are the best catalysts. The oxide resulting from the decomposition of such compounds as the pentahydroxide is for the most part the pentoxide Cb_2O_5 . This oxide, however, is reduced to a definite extent by hydrogen or by the gases and vaporous products resulting 65 from the decomposition of the hydrocarbons treated in the first stages of the process, so that the essential catalysts for the larger portion of the period of service are evidently the lower oxides CbO_2 , Cb_2O_3 , and CbO . 70

TANTALUM

Compounds of tantalum, such as for example, the pentoxide Ta_2O_5 and the tetroxide Ta_2O_4 , and possibly the sesquioxide Ta_2O_3 , which result from the reduction of the pentoxide are particularly efficient as catalysts for the present types of reactions but the invention is not limited to their use but may employ any of the catalytically active compounds of tantalum. Tantalum fluoride and the double fluoride of tantalum and potassium having the formula TaK_2F_7 are soluble in water and may be conveniently used in aqueous solution as ultimate sources of the oxides which result from the ignition of the precipitated hydroxide to form the pentoxide and the partial reduction of this oxide by hydrogen or the gases and vapors in contact with the catalyst in the normal operation of the process. The tantalum pentahydroxide may be precipitated from a solution of the double fluoride by the use of ammonium or alkali metal hydroxides or carbonates as precipitants, the hydrate being later ignited to form the pentoxide, which may undergo some reduction as already stated.

The most general method for adding promoting materials to the preferred base catalysts, which if properly prepared have a high adsorptive capacity, is to stir the prepared granules of from approximately 4 to 20 mesh into solutions of salts which will yield the desired promoting compounds on ignition under suitable conditions. In some instances the granules may be merely stirred in slightly warm solutions of salts until the dissolved compounds have been retained on the particles by absorption or occlusion, after which the particles are separated from the excess solvent by settling or filtration, washed with water to remove excess solution, and then ignited to produce the desired residual promoter. In cases of certain compounds of relatively low solubility it may be necessary to add the solution in successive portions to the adsorbent base catalyst with intermediate heating to drive off solvent in order to get the required quantity of promoter deposited upon the surface and in the pores of the base catalyst. The temperature used for drying and calcining after the addition of the promoters from solutions will depend entirely upon the individual characteristics of the compound added and no general ranges of temperature can be given for this step.

In some instances promoters may be deposited from solution by the addition of precipitants which cause the deposition of precipitates upon the catalyst granules. As a rule methods of mechanical mixing are not preferable, though in some instances in the case of hydrated or readily fusible compounds these may be mixed with the proper proportions of base catalysts and uniformly distributed during the condition of fusing or fluxing.

In regard to the relative proportions of base catalyst and promoting materials it may be stated in general that the latter are generally less than 10% by weight of the total composites. The effect upon the catalytic activity of the base catalysts caused by varying the percentage of any given compound or mixture of compounds deposited thereon is not a matter for exact calculation but more one for determination by experiment. Frequently good increases in catalytic effectiveness are obtainable by the deposition of as low as 1% or 2% of a promoting compound upon the surface and in the pores of the base

catalyst, though the general average is about 5%.

It has been found essential to the production of high yields of aromatics from aliphatic hydrocarbons when using the preferred types of catalysts that depending upon the aliphatic hydrocarbon or mixture of hydrocarbons being treated, temperatures from 400-700° C., should be employed, contact times of approximately 6 to 50 seconds and pressures approximately atmospheric. The use of subatmospheric pressures of the order of $\frac{1}{4}$ atmosphere may be beneficial in that reduced pressures generally favor selective dehydrogenation reactions but on the other hand moderately superatmospheric pressures usually of the order of less than 100 pounds per square inch tend to increase the capacity of commercial plant equipment so that in practice a balance is struck between these two factors. The times of contact most commonly employed with n-paraffinic or mono-olefinic hydrocarbons having from 6-12 carbon atoms to the molecule are of the order of 6-20 secs. It will be appreciated by those familiar with the art of hydrocarbon conversion in the presence of catalysts that the factors of temperature, pressure and time will frequently have to be adjusted from the results of preliminary experiments to produce the best results in any given instance. The criterion of the yield of aromatics will serve to fix the best conditions of operation. In a general sense the relations between time, temperature and pressure are preferably adjusted so that rather intensive conditions are employed of sufficient severity to insure a maximum amount of the desired cyclization reactions with a minimum of undesirable side reactions. If two short times of contact are employed the conversion reactions will not proceed beyond those of simple dehydrogenation and the yields of olefins and di-olefins will predominate over those of aromatics.

While the present process is particularly applicable to the production of the corresponding aromatics from an aliphatic hydrocarbon or a mixture of aliphatic hydrocarbons, the invention may also be employed to produce aromatics from aliphatic hydrocarbon mixtures such as distillates from paraffinic or mixed base crude petroleum. In this case the aromatic character of the distillates will have increased and as a rule the octane number will be higher. If desired and found feasible on a basis of concentration, the aromatics produced in the hydrocarbon mixture may be recovered as such by distillation into fractions of proper boiling range followed by chemical treatment with reagents capable of reacting selectively with them. Another method of aromatic concentration will involve the use of selective solvents such as liquid sulfur dioxide, alcohols, furfural, chlorex, etc.

In operating the process the general procedure is to vaporize hydrocarbons or mixtures of hydrocarbons and after heating the vapors to a suitable temperature within the ranges previously specified, to pass them through stationary masses of granular catalytic material in vertical cylindrical treating columns or banks of catalyst-containing tubes in parallel connection. Since the reactions are endothermic it may be necessary to apply some heat externally to maintain the best reaction temperature. After passing through the catalytic zone the products are submitted to fractionation to recover cuts or fractions containing the desired aromatic product with the separation of fixed gases, unconverted hydrocarbons and heavier residual materials, which may be disposed

of in any suitable manner depending upon their composition. The overall yield of aromatics may be increased by recycling the unconverted straight chain hydrocarbons to further treatment with 5 fresh material, although this is a more or less obvious expedient and not specifically characteristic of the present invention.

It is an important feature of the present process that the vapors undergoing dehydrogenation 10 should be free from all but traces of water vapor since the presence of any substantial amounts of steam reduces the catalytic selectivity of the composite catalysts to a marked degree. In view of the empirical state of the catalytic art, it is 15 not intended to submit a complete explanation of the reasons for the deleterious influence of water vapor on the course of the present type of catalyzed reactions, but it may be suggested that the action of the steam is to cause a partial hydration of such basic carriers as alumina and magnesium oxide and some of the active catalytic compounds due to preferential adsorption so that in effect the hydrocarbons are prevented from reaching or being adsorbed by the catalytically active surface.

The present types of catalysts are particularly effective in removing hydrogen from chain compounds in such a way that cyclization may be promoted without removal of hydrogen from end 30 carbon atoms so that both end and side alkyl groups may appear as substituents in benzene rings and it has been found that under proper operating conditions they do not tend to promote any great amount of undesirable side reactions leading to the deposition of carbon or 35 carbonaceous materials and for this reason show reactivity over relatively long periods of time. When their activity begins to diminish after a period of service, it is readily regenerated by the 40 simple expedient of oxidizing with air or other oxidizing gas at a moderately elevated temperature, usually within the range employed in the dehydrogenation and cyclization reactions. This 45 oxidation effectively removes traces of carbon deposits which contaminate the surface of the particles and decrease their efficiency. It is characteristic of the present types of catalysts that they may be repeatedly regenerated with only a very gradual loss of catalytic efficiency.

During oxidation with air or other oxidizing 50 gas mixture in regenerating partly spent material, there is evidence to indicate that when the lower oxides are employed, they are to a large extent, if not completely, oxidized to higher oxides which combine with basic carriers to form 55 compounds of variable composition. Later these compounds are decomposed by contact with reducing gases in the first stages of service to reform the lower oxides and regenerate the real catalyst and hence the catalytic activity.

Example I

A n-hexane charge obtained by the careful fractionation of a Pennsylvania crude oil was 65 found to have a boiling point of 68.8° C., and a refractive index of 1.3768 which corresponds closely to the properties of the pure compound. This material was vaporized and passed over a granular catalyst comprising an alumina base 70 supporting a minor proportion by weight of vanadium sesquioxide.

The catalyst was prepared by dissolving 15.4 parts by weight of ammonium metavanadate in 200 parts by weight of hot water and adding the 75 solution in two equal successive portions to 250

parts by weight of a 10-12 mesh activated alumina. After the addition of the first half of the solution the particles were somewhat damp and were dried at a steam temperature to remove excess water. After the heating the second half of the solution was added and the dehydration repeated. During the heating period ammonia and water were evolved leaving vanadium pentoxide deposited on the alumina particles.

The final steps in the preparation of the catalyst comprised heating at 200-250° C., for several hours, adding the particles to a catalyst chamber in which they were brought up to the necessary reaction temperature in a current of air, and then subjecting them to the action of 15 hydrogen at the operating temperature to produce the lower oxides, this change being accompanied by a change in color from yellow to bluish gray.

The yield of pure benzene from the n-hexane 20 when using a temperature of 510° C., substantially atmospheric pressure and a time of contact of 17 secs., was approximately 48% by weight of the n-hexane charged as a result of the single passage over the catalyst. By proper fractionation of the products and recycling of the unconverted material the ultimate yield of benzene 25 was finally brought to approximately 78%.

Example II

n-Heptane was treated with the same type of catalyst as in Example I at a temperature of 550° C., substantially atmospheric pressure and 30 10 secs. contact time. The yield of toluene on a once-through basis was found to be 48% by weight and again it was found that by recycling 35 the unconverted n-heptane that the yield of the desired toluene could ultimately be brought to 79%.

Example III

The general procedure in the manufacture of the catalyst was to dissolve the mixed fluoride of potassium and columbium in water and utilize this solution as a means of adding columbium compounds to a carrier. A saturated solution of this salt was made up in about 50 parts of water and this solution was then added to about 250 parts by weight of activated alumina which had been produced by calcining bauxite at a temperature of about 700° C., following by grinding and sizing to produce particles of approximately 8-12 mesh. Using the proportions stated the alumina exactly absorbed the solution and the particles were first dried at 100° C., for about 2 50 hours and the temperature was then raised to 350° C., in a period of 8 hours. After this calcining treatment the particles were placed in a reaction chamber and the residual compounds heated in a current of hydrogen at about 500° C., 55 when they were then ready for service.

n-Hexane was vaporized and passed over the granular catalyst, using a temperature of 515° C., substantially atmospheric pressure, and a time of contact of 18 secs. The yield of pure benzene 60 under these conditions was found to be 46% by weight of the normal n-hexane charged. By recycling of the unconverted material the ultimate yield of benzene was raised to 76%.

Example IV

n-Heptane was treated with the same type of catalyst as in Example III at a temperature of 565° C., substantially atmospheric pressure and 70 10 secs. contact time. The yield of toluene on a

once-through basis was found to be 46% by weight and again it was found that by recycling the unconverted n-heptane the yield of the desired toluene could ultimately be brought to 76%.

5

Example V

Owing to the relatively insolubility of most of the compounds of tantalum the method of dry mechanical mixing was resorted to in making up a catalyst. Thus one part by weight of tantalum dioxide was mixed with about 10 parts by weight of activated alumina which had been produced by calcining bauxite at a temperature of about 700° C., followed by grinding and sizing to produce particles of approximately 8-12 mesh. The catalyst particles were not treated with hydrogen on account of the known difficulty in reducing tantalum oxide although some reduction evidently took place when the hydrocarbon gas was passed over the mass in the first stages of the treatment.

The n-hexane described above was vaporized and passed over a granular catalyst comprising the alumina base supporting about 4% by weight of tantalum sesquioxide, using a temperature of 520° C., substantially atmospheric pressure, and a time of contact of 19 secs. The yield of pure benzene under these conditions was found to be 45% by weight of the normal n-hexane charged. By recycling of the unconverted material the ultimate yield of benzene was raised to 75%.

Example VI

n-Heptane was treated with the same type of catalyst as in Example V at a temperature of 565° C., substantially atmospheric pressure and 14 secs. contact time. The yield of toluene on a once-through basis was found to be 45% by weight and again it was found that by recycling the unconverted n-heptane that the yield of the desired toluene could ultimately be brought to 75%.

Example VII

To illustrate the results obtainable in the direct dehydrogenation and cyclization of olefins using catalysts according to the present invention, the conversion of 1-hexene into benzol using a vanadium oxide on alumina catalyst prepared generally in accordance with the method given in Example I may be cited. The vapors of the n-hexene were passed over the catalyst at a temperature of approximately 510° C., at atmospheric pressure at a rate corresponding to a total contact time of approximately 20 seconds, which produced a once-through yield of 72% benzol which could be raised to about 90% by recycling of unconverted olefin.

Example VIII

As a further example of the applicability of the present types of catalysts and the preferred conditions of operation for producing aromatics from olefins, an example involving the conversion of n-heptene to toluene may be cited. The catalyst employed was a mixture of columbium oxides on alumina and was prepared in general accordance with the procedure outlined in Example III. At a temperature of 505° C., substantially atmospheric pressure and a time of contact of about 18 seconds, there was produced a yield of toluene equal in weight to about 74% of the n-heptene charged. Recycling again increased the overall yield to 90%.

We claim as our invention:

1. A process for the production of aromatic

hydrocarbons from aliphatic hydrocarbons of from six to twelve carbon atoms, which comprises dehydrogenating and cyclizing the aliphatic hydrocarbon by subjection to a temperature of the order of 400 to 700° C., for a period of about 6 to 50 seconds, in the presence of a compound of a metal from the left hand column of group V of the periodic table and selected from the class consisting of vanadium, columbium and tantalum.

10

2. A process for the production of aromatic hydrocarbons from aliphatic hydrocarbons of from six to twelve carbon atoms, which comprises dehydrogenating by subjection to a temperature of the order of 400 to 700° C., for a period of about 6 to 50 seconds, in the presence of an oxide of a metal from the left hand column of group V of the periodic table and selected from the class consisting of vanadium, columbium and tantalum.

15

3. A process for the production of aromatic hydrocarbons from aliphatic hydrocarbons of from six to twelve carbon atoms, which comprises dehydrogenating and cyclizing the aliphatic hydrocarbon by subjection to a temperature of the order of 400 to 700° C., for a period of about 6 to 50 seconds, in the presence of a solid granular catalyst comprising essentially a major proportion of a carrier of relatively low catalytic activity supporting a minor proportion of a compound of a metal from the left hand column of group V of the periodic table and selected from the class consisting of vanadium, columbium and tantalum.

20

4. A process for the production of aromatic hydrocarbons from aliphatic hydrocarbons of from six to twelve carbon atoms, which comprises dehydrogenating and cyclizing the aliphatic hydrocarbon by subjection to a temperature of the order of 400 to 700° C., for a period of about 6 to 50 seconds, in the presence of a solid granular catalyst comprising essentially a major proportion of a carrier of relatively low catalytic activity supporting a minor proportion of an oxide of a metal from the left hand column of group V of the periodic table and selected from the class consisting of vanadium, columbium and tantalum.

25

5. A process for the production of aromatic hydrocarbons from aliphatic hydrocarbons of from six to twelve carbon atoms, which comprises dehydrogenating and cyclizing the aliphatic hydrocarbon by subjection to a temperature of the order of 400 to 700° C., for a time period of less than 50 seconds but sufficient to dehydrogenate and cyclize the aliphatic hydrocarbon, in the presence of a compound of a metal from the left hand column of group V of the periodic table and selected from the class consisting of vanadium, columbium and tantalum.

30

6. A process for the production of aromatic hydrocarbons from aliphatic hydrocarbons of from six to twelve carbon atoms, which comprises dehydrogenating by subjection to a temperature of the order of 400 to 700° C., for a time period of less than 50 seconds but sufficient to dehydrogenate and cyclize the aliphatic hydrocarbon, in the presence of an oxide of a metal from the left hand column of group V of the periodic table and selected from the class consisting of vanadium, columbium and tantalum.

35

7. A process for the production of aromatic hydrocarbons from aliphatic hydrocarbons of from six to twelve carbon atoms, which comprises dehydrogenating and cyclizing the aliphatic hydrocarbon by subjection to a temperature of the

40

45

50

55

60

65

70

75

order of 400 to 700° C., for a time period of less than 50 seconds but sufficient to dehydrogenate and cyclize the aliphatic hydrocarbon, in the presence of a solid granular catalyst comprising 5 essentially a major proportion of a carrier of relatively low catalytic activity supporting a minor proportion of a compound of a metal from the left hand column of group V of the periodic table and selected from the class consisting of vanadium, columbium and tantalum.

8. A process for the production of aromatic hydrocarbons from aliphatic hydrocarbons of from six to twelve carbon atoms, which comprises dehydrogenating and cyclizing the aliphatic hy-

drocarbon by subjection to a temperature of the order of 400 to 700° C., for a time period of less than 50 seconds but sufficient to dehydrogenate and cyclize the aliphatic hydrocarbon, in the presence of a solid granular catalyst comprising 5 essentially a major proportion of a carrier of relatively low catalytic activity supporting a minor proportion of an oxide of a metal from the left hand column of group V of the periodic table and selected from the class consisting of vanadium, 10 columbium and tantalum.
